(57) **CLAIM**

The ornamental design for a table as shown and described.

DESCRIPTION

FIG. 1 is a top perspective view of a first embodiment of a table;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged fragmentary perspective showing one of the legs of the table isolated for clarity of disclosure.

FIG. 10 is a top perspective view of a second embodiment of a table;

FIG. 11 is a bottom perspective view thereof;

FIG. 12 is a top perspective view of a third embodiment of a table; and,

FIG. 13 is a bottom perspective view thereof.

The long-dash short-dash broken lines show the boundaries of the claim and form no part thereof. The even dash broken lines show portions of the table that form no part of the claimed design. The length of the table is shown with a symbolic break. The appearance of any portion of the table between the break lines forms no part of the claimed design.
